VARIABLE FLUID-OPERATED ELEVATING TRUCK

Daniel E. Hennessy, Watertown, Mass., assignor to Lewis-Shepard Company, Watertown, Mass., a corporation of Massachusetts

Application September 9, 1932, Serial No. 632,358

13 Claims.

(Cl. 254—2)

This invention relates to improvements in elevating trucks adapted to be introduced beneath the article to be raised, such as a platform or skid, and having upwardly movable load supporting means with mechanism for raising the same to lift the article, skid, or platform, and transport it from one place to another.

Such trucks are ordinarily used for transporting skids or platforms carrying light or heavy loads and in which the under clearance of the skid or platform may vary from seven to eleven inches, or more.

It has heretofore been customary to make trucks for practically each height of platform under clearance. Furthermore, if a truck 7" high when the load supporting means is in lowered position, having a 6" lift for the load supporting means, is employed to raise a platform having several inches under clearance, with a sufficiently high mechanical lifting ratio required for heavy duty, considerable time would be consumed to raise the load supporting means into engagement with the platform before the lifting of the platform is begun.

One of the objects of the invention is to provide an elevating truck which may be used efficiently with any standard height skid or platform.

Another object of the invention is to provide an elevating truck of this character with means for elevating the load supporting means to lift loads varying from light to very heavy loads in which the force required to be applied to the lifting lever does not exceed a reasonable maximum, while at the same time the total lifting operation may be performed in a minimum time.

Another object of the invention is to provide an elevating truck comprising a vertical hydraulic jack provided with a single lifting ram operable by a plurality of pumping elements and having means selectively operable to enable one or more of the pumps to be actuated to raise the ram.

A further object of the invention is to provide an elevating truck having a hydraulic jack provided with a single lifting or ram element operable by a plurality of pumps of different capacity, with means selectively operable to actuate one or more of the pumps, and thereby to enable the load supporting means to be raised rapidly or more slowly with increased effective power applied through the same actuating mechanism.

In elevating trucks having a hydraulic lifting jack heretofore constructed, the lifting jack has been located in positions slightly inclined upwardly from the horizontal and the relatively moving surfaces so arranged that a seepage takes place around them resulting in the loss of reserve

fluid, thereby greatly impairing the efficiency of the lifting mechanism.

Another object of the invention is to provide an elevating truck having a hydraulic jack for raising the load supporting means in which loss of fluid will not occur. This is accomplished by providing a construction in which the lifting jack is at all times in a vertical or substantially vertical position.

More specifically the object of the invention is to provide an elevating truck with a hydraulic jack comprising a reservoir, a ram cylinder and ram and a pump or pumps for drawing liquid from the reservoir and discharging it under pressure into the ram cylinder, so constructed as to avoid any loss of liquid by seepage or otherwise.

A further object of the invention is to provide a lifting truck having a hydraulic lifting jack in which the lifting force of the ram is directly applied to the load supporting means in a vertical direction.

Another object of the invention is to provide an elevating truck having a hydraulic lifting jack with means for preventing damage from overloading.

Another object of the invention is to provide an elevating truck having a hydraulic lifting jack with means for positively arresting the upward movement of the load supporting means at a predetermined height in combination with means for preventing overload if actuation of the pump or pumps is continued after the arrest of the upward movement of the load supporting means.

A further object of the invention is to provide a graduated manually operable release for the fluid pressure in the ram cylinder to control the descent of the load supporting means to any desired rate of speed.

Another object of the invention is to provide an elevating truck having a hydraulic jack comprising a vertically movable ram operable to apply a vertical lifting force to the front end of the load supporting means, with novel and sturdy mechanism operable by the lifting movement of the front end of the load supporting means to raise the rear end of the load supporting means in synchronism with the upward movement of the front end of the load supporting means.

These and other objects and features of the invention will more fully appear from the following description and the accompanying drawings and will be particularly pointed out in the claims.

In the drawings:

Fig. 1 is a side elevation of an elevating truck

embodying my invention having a hydraulic jack for lifting the load supporting means operable by vertical swinging movement of the tongue;

Fig. 2 is a similar side elevation of a portion of 5 a lifting truck embodying the invention in which the hydraulic jack is operated by a foot lever;

Fig. 3 is a plan view of the lifting truck illustrated in Fig. 1 showing a lifting jack having a vertical ram cylinder and ram, and a plurality of 10 pumps for supplying fluid under pressure thereto;

Fig. 4 is a detail view illustrating the selectively operable means employed for detachably connecting the actuating lever to one of the pump plungers, it being understood that such mechanism may 15 be employed for connecting either pump plunger to the actuating lever or levers;

Fig. 5 is a horizontal sectional view of the lifting jack on line 5—5 Fig. 6; and,

Fig. 6 is a view, partly in vertical section, upon 20 the broken line 6—6, Fig. 5, showing, also, pump cylinders and plungers therefor of different capacity.

The preferred form of elevating truck illustrated in the drawings comprises a main frame having side bars 1 and 2 connected at their front ends to a head 3 and diverging rearwardly therefrom and provided at their rear ends with bearings 4 for a rear axle 5 having wheels 6 mounted upon 25 it preferably outside of the side frames 1 and 2, thereby providing a wire rear end support for the truck.

Suitable steering mechanism is rotatably mounted in the head 3 of the frame. As illustrated herein, the steering mechanism comprises a vertical steering post 7 rotatably mounted in the head 3 and provided with an annular bearing 8 underlying and engaging the under face of the head, with a yoke 9 extending downwardly therefrom, the lower ends of the arms of which support a shaft 10 for the front steering wheel or wheels 11. The steering post 7 extends upwardly beyond the upper surface of the head 3 and has clamped upon it a split collar 12 provided with a 30 upwardly and forwardly extending ears 13 with a shaft 14 forming a fulcrum for the tongue mounted in said ears adjacent the upper ends thereof. The tongue preferably comprises a cylindrical tube or pipe 15 having at its upper end the usual transverse handles (not shown) and having its 35 lower end extending into and secured to the bifurcated cylindrical upper end 16 of a tongue member which is fulcrumed upon the shaft 14 and provided with a bifurcated downward and 40 rearward extension 17 having flat end surfaces 18 adapted to engage the collar upon the steering post in such manner as to limit the rearward swinging movement of the tongue and thereby enable it to be employed to push the truck rearwardly.

The load supporting means preferably comprises parallel side bars 19 and 20 in the form of angle bars having their horizontal flanges overlying the frame and their vertical flanges 45 outside of the side bars of the frame and connected at their rear ends by a transverse girder 21, preferably in the form of an angle bar, having its horizontal flange flush with the upper surface of the side bars of the load supporting 50 means, and the vertical flange thereof extending downwardly and preferably bent circularly at its ends to avoid sharp corners. The transverse girder desirably extends beyond the side bars of the load supporting means to approximately the 55 outer vertical plane of the rear wheels.

The front ends of the side bars of the load supporting means are connected to an integral standard 22 having a transverse web 23 forming a dash board and upwardly extending members 24 curved forwardly at their upper ends forming a head overlying the lifting ram of the hydraulic jack, which will hereinafter be described. The head 22 of the platform is also provided with integral, downwardly extending bosses or brackets 25 which provide journals for the transverse shaft 26 upon one of which one end of a bell crank lever 27 is mounted. The bell crank lever 27 is fulcrumed upon a shaft 28 carried by suitable brackets 29 mounted upon the side bars 1 and 2. The other arms of the bell crank lever preferably comprise pairs of bosses 30 and 31 in each of which is mounted a shaft 32 upon which a T-shaped coupling 33 is pivotally mounted. Tension rods 34 desirably are adjustably connected to the couplings 33 by screw threaded unions and extend rearwardly therefrom longitudinally of the truck and are connected at their rear ends by reversely screw threaded couplings to T-shaped members 35 which are mounted upon shafts 36 in pairs of webs 37 and 38 of a lifting lever 39 which is pivotally mounted upon the rear axle and the rear end of which is provided with a cylindrical boss 40 having a shaft 41 mounted therein and provided at its end with anti-friction means, such as rollers 42 which underlie and engage the underfaces of the horizontal flanges of the side bars of the load supporting means.

By reason of this construction the application of a vertical lifting force to the head of the load supporting means will cause upward movement 35 thereof which in turn will raise the forwardly extending arm of the bell crank lever 27, thereby swinging the other arms or bosses 30, 31 downwardly and forwardly, thus drawing the tension rods 34 forwardly, and in turn swinging the rear 40 lifting lever which is pivoted upon the rear axle upwardly and forwardly, so that the rollers upon the end thereof will raise the rear end of the load supporting means. The relative dimensions of the parts thus described are so constructed that 45 the rear end of the load supporting means will be lifted in substantial synchronism with the lifting movement of the front end of the load supporting means.

One of the principal objects of the invention, as 50 above described, is to provide a hydraulic jack comprising a ram cylinder having a ram so constructed and positioned as to apply a lifting force to the load supporting means with a plurality of pumps, preferably of different capacities, operable selectively or conjointly to supply fluid under 55 pressure to the ram cylinder, so that by supplying the fluid under pressure at a rapid rate to the ram cylinder the load supporting means may be elevated quickly, or by supplying fluid under 60 greater pressure from one of the pumps an increased lifting power will be effected to lift the load supporting means when carrying a heavy load, at a relatively low rate of speed, and without requiring substantially greater application of 65 force upon the mechanism for operating a single pump than would be required to operate a plurality of pumps with a lighter load.

In the present construction the ram cylinder, and preferably also the pump cylinders are in a 70 vertical position with suitable valve connections between the reservoir and the pumps and between the pumps and the ram cylinder. By reason of this construction there is no likelihood of loss of fluid by reason of seepage or in any other manner. 75

Any suitable means may be employed for actuating the pump or pumps of a hydraulic jack. As illustrated in Fig. 1 the pump plungers are reciprocated by an actuating lever which in turn is oscillated by vertical swinging movements of the steering tongue, suitable connections between the actuating lever and the steering tongue being provided to permit disengagement of the steering tongue therefrom when it is to be used for steering purposes. Means are also provided for detachably connecting either or both of the pump plungers to the actuating lever, so that either pump may be operated singly or both conjointly to force fluid under pressure into the ram cylinder.

The invention furthermore includes an exhaust conduit leading from the ram cylinder to the reservoir of the jack, with means manually operable to provide a graduated release of the fluid under pressure from the ram cylinder, thereby enabling the operator to permit the load supporting means to descend at any desirable speed.

The invention further includes automatic means for preventing the production of excessive pressure in the ram cylinder which might damage or break the lifting mechanism.

In the particular embodiment of the invention shown in the drawings the lifting jack comprises a vertical block 43, preferably of general rectangular cross section, having downwardly extending bosses which are mounted upon a shaft 44 journaled at its ends in the side frames 1 and 2. The block 43 desirably also is provided with a plurality of bosses 45 having bearings therein in alinement with like bearings in bosses 46 extending upwardly and rearwardly from the head 3. The bosses 45 and 46 are connected by a shaft 47 extending through the alined bearings in said bosses.

By reason of this construction the block 43 is maintained rigidly in vertical position, as illustrated in Fig. 1.

The block 43 of the jack is cored to provide a reservoir 48 of ample capacity to contain sufficient oil, or other fluid, to supply the pumps and the ram cylinder. The block 43 has centrally of its width an integral vertical ram cylinder 49 in which a ram 50 is reciprocably mounted. Vertical pump cylinders 51 and 52 are arranged symmetrically upon opposite sides of the ram cylinder 49 and are respectively provided with plungers 53 and 54. The pumps 51 and 52 may be of the same diameter, or of different diameters, as illustrated in Figs. 5 and 6.

Suitable valved connections are provided for conducting liquid from the reservoir to the pump cylinders, and from the pump cylinders to the ram cylinder. In the particular construction illustrated the oil passes from the reservoir 48 through a conduit 55 to the pump cylinder 51. The admission of oil to the conduit 55 is controlled by a poppet valve having a valve seat or casing 56 seated in an inlet leading to the conduit 55 and having screw threaded engagement with the wall of the inlet. The flow of oil through the inlet is controlled by a spring actuated poppet valve 57 normally held against the under face of the valve seat 56 by a spring 58 interposed between the upper end of the valve seat member 56 and a suitable abutment secured to the upper end of the valve stem. The upward movement of the plunger 53 will create a partial vacuum in the lower part of the pump cylinder 51, thereby causing the fluid in the reservoir to exert sufficient pressure upon the valve 57 to depress it from its seat, so that the liquid will flow from

the reservoir through the conduit 55 into the pump cylinder 51. When the upward movement of the plunger has ceased, the spring 58 of the poppet valve will return it to its seat, thereby closing the inlet and upon downward movement of the plunger 53 liquid will be forced through the conduit into the chamber 59 beneath the poppet valve 57 from which it is forced through an outlet 60 into a conduit 61 which communicates with the lower end of the ram cylinder 49. A valve 62, having a valve stem of small diameter extending into the outlet 60, is normally held in engagement with the lower walls of the outlet orifices 60 by a helical spring 63, the upper end of which engages the valve 62 and the lower end of which desirably is seated in a depression in a plug 64 suitably secured to the block. Downward movement of the plunger 53 therefore forces the liquid from the lower portion of the pump cylinder 51 through the conduit 55, thence through the outlet 60, displacing the valve 62 so that liquid under pressure is caused to flow through the conduit 61 into the lower end of the ram cylinder 49. When the downward movement of the plunger 53 ceases, the valve 62 is seated by the action of the spring 63, thereby preventing liquid from flowing backwardly from the ram cylinder into the pump.

Similar conduit 65 having a like poppet valve 66 in the inlet, therefore, establishes communication between the reservoir and the other pump cylinder 52, and upon depression of the plunger 54 in said cylinder the liquid is caused to flow through the outlet 67 into a conduit 68, the end of which communicates with the lower portion of the ram cylinder. A spring-pressed valve 69, similar to the spring-pressed valve 62, is arranged to prevent backward flow from the ram cylinder into the pump in the manner heretofore described.

Inasmuch as the fluid pressure transmitted from a pump cylinder to the ram cylinder, when a predetermined force is applied to the pump cylinder, is inversely proportional to the respective cross sectional areas of the pump cylinder and ram cylinder, the provision of a plurality of pumps selectively operable to force fluid under pressure from the reservoir into the ram cylinder enables the operator, while exerting substantially the same force upon an actuating lever, to exert different forces upon the ram of the ram cylinder. When two or more pumps are reciprocated conjointly by the actuating means, the force exerted upon the ram approximates the relative inverse proportion of the sum of the cross sectional areas of the pump cylinders to that of the ram cylinder. The amount of fluid, however, which is forced from the pump cylinder to the ram cylinder, when the plunger is given a predetermined stroke, varies in amount in direct proportion to the relative cross sectional areas of the pump cylinder and ram cylinder. Consequently, with a smaller pump actuated by the same force, a greater number of reciprocations is necessary to raise the ram cylinder a predetermined distance. As a consequence, the selective operation of a plurality of pumps of different diameters, either singly or conjointly, enables the operator employing substantially the same force upon the actuating means to raise the ram cylinder rapidly when a light load is to be lifted, less rapidly when an intermediate load is to be lifted, and still more slowly when a maximum load is to be lifted.

Means for preventing the generation of an ex-

cessive fluid pressure in the ram cylinder is provided. As illustrated, the mechanism for accomplishing this purpose comprises a nipple 70 having a screw threaded hollow stem which engages 5 a complementary internal thread in the walls of a boss 71 which is bored to communicate with the conduit 68. A cylindrical valve casing 72 is externally threaded upon the nipple 70 and encloses a valve 73 which when seated engages the 10 upper face of the nipple. The valve 73 is provided with a stem 74 which extends axially through the casing 72 and a heavy spring 75 interposed between the upper end of the valve casing and the valve 73 serves to hold the valve normally in 15 seated position unless sufficient pressure is built up to raise the valve. The valve casing is provided with a plurality of ports 76 through which the liquid may escape into the reservoir when the valve 73 is raised from its seat by such excessive 20 pressure.

Any suitable manually operable means for permitting graduated release of the liquid from the ram cylinder may be provided. In the preferred construction the conduit 68 is provided with a 25 vertical branch 77 which communicates with an enlarged chamber in a boss 78 extending upwardly from the lower wall of the reservoir. The ball valve 79 is seated at the upper end of the conduit 77 and is adapted to be held in seated 30 position by a rod 80, the lower end of which has screw threaded engagement with the internal wall of the boss 78. The lower end of the rod 80 desirably is slotted crosswise to a distance slightly above the upper end of the boss when 35 the ball is held in seated position to provide a delicately adjustable outlet 81 which, when the rod is raised sufficiently to release the ball from its seat, will permit liquid to flow from the conduit 77 through the enlarged chamber in the boss 40 78 and thence through the adjustable outlet 81 into the reservoir. By reason of this construction the release of fluid under pressure from the ram cylinder can be very accurately controlled as the effective area of the outlet 81 is determined by 45 the distance between the wall forming the end of the slot and the upper end of the boss 78. The screw threaded connection between the lower end of the rod 80 and the boss 78 also enables delicate adjustment of the ball valve 79 relatively 50 to its seat, and the sinuous course followed by the fluid under pressure passing around the ball, thence upwardly through the slot in the lower end of the rod, and finally through the outlet, provides a delicate control which will enable the 55 load supporting means to be lowered at any desired rate irrespective of the weight of the load upon it. The rod 80 desirably extends through a suitable bearing in the cover 82 for the reservoir and is provided with a handle 83 by which it can be conveniently rotated by the operator.

In the constructions illustrated in Figs. 1 to 3 the upwardly extending curved members 24 of the standards 22 are provided at their outer ends with bosses 84 in which a shaft 85 is mounted and an anti-friction roller 86 engages the upper end of the ram 59, whereby it exerts a vertical pressure upon the under side of the overhanging end of the standard 22 and consequently upon the load supporting means.

Any suitable means may be provided for selectively actuating the pump plungers singly or 70 conjointly. In the construction illustrated in Figs. 1, 3, and 4, the actuating mechanism comprises levers fulcrumed upon the shaft 47 which 75 is mounted in the bosses 45 and 46, with means

for detachably connecting the levers at one end to the tongue extension and with means for detachably connecting the opposite ends selectively to one or both of the pump plungers 53 and 54.

In the preferred construction illustrated each lever comprises an arm 87 having a boss 88 which is fixedly secured to the shaft 47 and another arm 89 having a similar boss also secured to the shaft 47. The front ends of the arms 89 are pivotally connected to vertical legs 90 10 of a yoke having a horizontal portion 91 adapted to be swung over the lower end of the tongue extensions 17. The horizontal member 91 of the yoke is provided with a central downwardly extending boss or arm 92 having a recess 93 adapted 15 to engage a pin 94 mounted in the rearward extensions 17 of the tongue. By reason of the pivotal connection of the yoke arms 90 to the arm 89 of the actuating lever, the yoke may be swung forwardly to cause engagement of the recess 93 20 with the pin 94 or it may be swung rearwardly therefrom, into engagement with the block 43, out of engagement with the tongue extension, thereby permitting the tongue to have a free 25 steering movement.

The other arms 87 of the actuating levers are provided with outwardly extending studs 95, (see Figs. 1 and 4) adapted to be engaged by recesses in the lower ends of links 96 the upper ends of which are connected to pins 97 which 30 extend through a cross head 98 enclosing the upper end of the plunger 53 and reciprocably mounted in a cylindrical guide 99 of larger bore than that of the pump cylinder, the walls of the guiding cylinder 99 being provided with suitable 35 slots 100 to permit vertical movement of the pin 97 therein.

Means desirably are provided for selectively retaining the links 96 respectively in such position that the recesses therein will engage the 40 pins 95, or for holding the links in a position in which such engagement cannot take place. A convenient device of this character comprises an arm 101 pivotally mounted upon the pin 97 45 upon which the link 96 is mounted, the arm 101 being provided with a counterweight 102 and with oppositely disposed lugs 103 and 104 adapted respectively to be swung into engagement with the link 96, so that when the lug 103 engages the link 96 the counterweight 102 will hold the 50 lower recessed end of the link in engagement with the pin 95, and conversely when the counterweighted arm 101 is swung forwardly to cause the lug 104 to engage the opposite side of the link, it will hold the lower end of the link 55 rearwardly so that its recess cannot engage the pin 95.

Similar constructions are provided for detachably connecting the plunger 54 to a like actuating lever. By reason of this construction, therefore, the actuating levers can be selectively connected to either or both of the pump plungers 53 and 54 and the opposite end of the actuating levers may be connected to or disengaged from the rearward extension of the tongue.

Where in the operation of the device it is desirable to raise the load supporting means rapidly, as from its lowest position, to engage the under face of a platform having high under-clearance, or to raise the relatively light load 70 rapidly, the counterweighted arms 101 may be swung backwardly to cause engagement of the recesses at the lower ends of the links 96 with the pins 95 upon the arms 86 of the actuating levers. The yoke at the opposite ends of the 75

actuating levers may then be swung forwardly to cause engagement of the recesses 93 in the downwardly extending boss 92 of the yoke, thereby connecting the tongue extension to the actuating levers. Vertical swinging movements of the tongue will, therefore, cause the actuating levers to reciprocate the plungers of both pumps in unison, thereby drawing a maximum amount of liquid from the reservoir and forcing it into the ram cylinder under relatively low pressure, but at a rate sufficient to raise the ram and consequently the load supporting means rapidly. If a load of moderate weight is to be raised which, however, would necessitate a considerable exertion upon the tongue by the operator, the counterweighted lever 101, which connects the plunger of the smaller pump to the actuating lever, may be swung forwardly to disengage the link 96 from the pin 97 of the pump plunger. Vertical swinging movement of the tongue will thereupon actuate only the larger pump.

The quantity of fluid drawn from the reservoir and forced by such larger pump into the ram cylinder will be less in quantity at each stroke than where both pumps are actuated simultaneously. Consequently, a greater number of reciprocations of the tongue will be required to raise the ram, and if substantially the same force is exerted upon the tongue by the operator the fluid under pressure will be forced by the pump into the ram cylinder under greater pressure, thereby enabling the heavier load to be raised with equal exertion upon the part of the operator, with the exception that he will be required to swing the tongue downwardly and upwardly a greater number of times to raise the load the same distance.

If a much heavier load is to be raised by the load supporting means, the counterweighted arm 101 of the larger pump may be rotated forwardly to detach the link 96 from the pin 95 of the actuating lever and the counterweighted arm 101 which controls the lever 96 of the smaller pump may be rotated rearwardly to cause engagement of the lower end 96 of the link with the pin 95 upon the actuating lever for the smaller pump. A greater number of reciprocations of the plunger of the smaller pump will be required to raise the ram of the ram cylinder through the same distance, but the liquid will be supplied to the ram cylinder under still higher pressure as will be readily understood, thus enabling a maximum load to be lifted without undue exertion upon the part of the operator. When the load has been lifted, either by a single pump or by the action of the pumps conjointly, the load supporting means will be retained in elevated position so long as the rod 80 is in the position in which it holds the ball valve 79 firmly upon its seat. When it is desired to lower the load, the operator may grasp the handle 83 of the rod 80 and rotate it in a reverse direction to such an extent as will enable the load to descend at the desired rate of speed which is controlled by the escape of liquid from the outlet 81 in the slotted lower end of the rod 80 into the reservoir.

In lifting loads for transportation, and particularly the usual skids or platforms, it is necessary to raise the same a sufficient distance to avoid possible contact with the floor, but is undesirable to lift the skid or platform to any considerably greater height as such additional elevation of the platform not only requires additional time during the lifting operation, but also

additional time for the skid or platform to be deposited upon the floor. Furthermore, the raising of the load to an unnecessary and undesirable height decreases the stability of the truck if a high load is being transported.

The present invention contemplates the provision of preferably adjustable means for limiting the maximum height to which the load supporting means can be raised. This is accomplished in the preferred construction illustrated by providing adjustable stops, such as nuts 105, upon one or both of the tension rods 34 to engage a transverse girder 106, secured, preferably by welding, to the side frames 1 and 2, when the load supporting means has been raised to a predetermined height. If the pumps are actuated after the engagement by the stop or stops with the abutment, the excess of fluid pressure transmitted from the pumps to the ram cylinder will be relieved by the unseating of the relief or safety valve 73.

A modified embodiment of the invention is illustrated in Fig. 2 of the drawings which illustrates an elevating truck having a frame comprising side bars connected at their front ends by a head 3 provided with steering mechanism including a vertical swinging tongue, as heretofore described, and mechanism operable by the lifting of the front end of the load supporting means to raise the rear end of the load supporting means in synchronism therewith in the manner heretofore described, but which differs from the mechanism previously described in that the block 43, which contains the reservoir, the ram and pump cylinders, is pivotally mounted upon the transverse shaft 44, and in that the forwardly curved extension 24 of the standard 22 is pivotally connected by the shaft 85 to lugs 107 integral with and extending upwardly from the upper end of the ram 50.

By reason of these pivotal connections the block 43 is adapted to oscillate slightly about the pivot 44 during the raising and lowering movements of the load supporting means caused by the movement of the bell crank lever 27 which supports the front end of the load supporting means.

The construction illustrated in Fig. 2 also differs from that previously described in that links 108, which are pivotally mounted at their upper ends upon the pins 97 which extend through the pump plungers 53 and 54 and their cross heads, are of greater length and are provided with recesses 109 adapted detachably to engage suitable pins or studs 110 which are actuated by a foot lever or pedal 111. In the construction illustrated the pedal 111 is fixedly secured to a transverse shaft 112 mounted in suitable bearings in the side frames 1 and 2, and a spring 113, coiled upon the shaft 112 and having one end attached thereto and the other end engaging a suitable abutment, normally holds the foot pedal in elevated position, as illustrated. One of the links 108 may be detachably secured to the pin 110 upon the lever 111, while the other link 108 may be similarly detachably secured to a like pin projecting from another lever arm which is fixedly secured to the shaft 112 and extends forwardly in parallelism with the pedal 111.

It will, therefore, be obvious that in either of the constructions above described the pump plungers are adapted to be selectively reciprocated either singly or conjointly to raise the ram and thereby to raise the load supporting means, when carrying different loads, with a force applied to the pump-actuating means which does

not exceed a reasonable maximum while enabling the lifting operation to be performed in a minimum time.

It will be understood that the particular embodiments of the invention disclosed herein are of an illustrative character and not restrictive and that various changes in form, construction and arrangement of parts may be made within the spirit and scope of the following claims.

10 Having thus described the invention, what is claimed as new, and desired to be secured by Letters Patent, is:

1. An elevating truck comprising a wheel-supported frame, load supporting means mounted thereon and movable upwardly relative thereto, a fluid-operated jack mounted in said main frame comprising a vertical ram cylinder, a ram reciprocably mounted therein and means operable by said ram to lift said load-supporting means, a plurality of pump cylinders of different diameters each having an independently valved connection with said ram cylinder, a plunger for each pump cylinder, a lifting lever and selectively operable means for connecting either of said pump plungers to said lifting lever or for connecting all of said plungers to said lifting lever for simultaneous operation.

2. An elevating truck comprising a main frame having rear wheels, a head, steering mechanism rotatively mounted in said head having a tongue mounted to swing vertically, load supporting means mounted upon said frame and movable upwardly relative thereto, a fluid-operated jack mounted in said frame comprising a vertical ram cylinder, a ram reciprocably mounted therein and means operable by said ram to lift said load supporting means, a plurality of pump cylinders of different diameters each having an independent valved connection with said ram cylinder, a plunger for each pump cylinder and means selectively operable for connecting either of said pump cylinders to said tongue or for connecting all of said pump cylinders to said tongue for simultaneous operation.

3. An elevating truck comprising a frame having rear wheels, a head and steering mechanism rotatively mounted therein having a tongue mounted to swing vertically, a fluid-operated lifting jack mounted on said frame comprising a vertical ram cylinder and a ram reciprocably mounted therein, a platform supported upon said main frame by parallel links and having a head overlying said ram, a plurality of pump cylinders of different diameters each having valved connection with said ram cylinder, a plunger for each pump cylinder and selectively operable means for connecting either of said pump plungers to said tongue or for connecting all of said plungers to said tongue.

4. An elevating truck comprising a frame having rear wheels, a head and steering mechanism rotatably mounted therein and having a tongue mounted to swing vertically, a jack comprising a cylinder block located in proximity to said head having a reservoir for liquid, a central vertical ram cylinder, and a plurality of pump cylinders each having a valved connection with said reservoir and an independent valved connection with said ram cylinder, a ram reciprocably mounted in said ram cylinder, plungers reciprocably mounted in the respective pump cylinders, load supporting means mounted on said frame, means operable by the vertical movement of said ram to raise said load supporting means, an actuating lever, and means for releasably connecting one

end of said actuating lever to each of the plungers for the respective pump cylinders selectively to cause individual or conjoint simultaneous actuation thereof, and means for releasably connecting the other arm of said actuating lever to said tongue whereby vertical swinging movement of the tongue will actuate the selected plunger or plungers.

5. An elevating truck comprising a frame having rear wheels, a head and steering mechanism rotatably mounted therein and having a tongue mounted to swing vertically, a jack comprising a cylinder block located in proximity to said head having a reservoir for liquid, a central vertical ram cylinder, and vertical pump cylinders located on opposite sides of said ram cylinder each having a valved connection with said reservoir and an independent valved connection with said ram cylinder, a ram reciprocably mounted in said ram cylinder, plungers reciprocably mounted in the respective pump cylinders, load supporting means mounted on said frame having a head overlying said ram, an actuating lever, and means detachably connecting one end of said actuating lever to the respective pump plungers selectively to cause individual or conjoint simultaneous actuation thereof, and means for releasably connecting the other arm of said actuating lever to said tongue whereby vertical swinging movement of the tongue will actuate the selected plunger or plungers.

6. An elevating truck comprising a frame having rear wheels, a head and steering mechanism rotatably mounted therein, a jack comprising a cylinder block located in proximity to said head having a reservoir for liquid, a central vertical ram cylinder, and a plurality of pump cylinders each having a valved connection with said reservoir and an independent valved connection with said ram cylinder, a ram reciprocably mounted in said ram cylinder, plungers reciprocably mounted in the respective pump cylinders, load supporting means mounted on said frame having a head overlying said ram operable by the vertical movement of said ram to raise said load supporting means, an actuating lever, means for releasably connecting one end of said actuating lever to the plungers for the respective pump cylinders selectively to cause individual or conjoint actuation of said plungers, means for releasing fluid under pressure from said ram cylinder including a valve and a member having screw threaded connection with said head operable to control said valve and thereby to regulate with accuracy the rate of descent of the load supporting means.

7. An elevating truck comprising a frame having rear wheels, a head and steering mechanism rotatably mounted therein, a jack comprising a cylinder block located in proximity to said head having a reservoir for liquid, a central vertical ram cylinder, and a plurality of pump cylinders each having a valved connection with said reservoir and an independent valved connection with said ram cylinder, a ram reciprocably mounted in said ram cylinder, plungers reciprocably mounted in the respective pump cylinders, load supporting means mounted on said frame having a head overlying said ram operable by the vertical movement of said ram to raise said load supporting means, an actuating lever, means for releasably connecting one end of said actuating lever to the plungers for the respective pump cylinders selectively to cause individual or conjoint actuation of said plungers, an exhaust con-

duit leading from said ram cylinder to said reservoir having therein a ball valve, and a manually operable rod having screw threaded engagement with said head operable to force said ball valve upon its seat or to release said valve gradually therefrom and thereby to determine the rate of escape of fluid from said ram cylinder.

8. An elevating truck comprising a frame having rear wheels, a head and steering mechanism 10 rotatably mounted therein having a tongue mounted to swing vertically, a cylinder block mounted upon said frame in proximity to said head having a reservoir for liquid, a central vertical ram cylinder, vertical pump cylinders of different diameters located on opposite sides of said 15 ram cylinder each having a valved connection with said reservoir and an independent valved connection with said ram cylinder, a ram reciprocably mounted in said ram cylinder, plungers reciprocably mounted in said pump cylinders, load supporting means mounted on said frame having a head rigid therewith extending over said ram, an actuating lever pivotally mounted on the head of said frame, independent means 20 releasably connecting said actuating lever to the respective pump plungers, and means releasably connecting said lever to the tongue, whereby said actuating lever may be operated by the vertical swinging movement of said tongue or released 25 from said tongue to permit free steering movement of said tongue, an exhaust conduit leading from said ram cylinder to said reservoir, and manually operable means for controlling the escape of fluid from said ram cylinder thereby 30 to regulate the rate of descent of said load supporting means.

9. An elevating truck comprising a frame having rear wheels, a head and steering mechanism 40 rotatably mounted therein having a tongue mounted to swing vertically, a cylinder block mounted upon said frame in proximity to said head having a reservoir for liquid, a central vertical ram cylinder, vertical pump cylinders of different diameters located on opposite sides of said ram cylinder each having a valved connection, and an independent valved connection with said reservoir and said ram cylinder, respectively, a ram reciprocably mounted in said ram cylinder, plungers reciprocably mounted in said pump cylinders, load supporting means mounted on said 45 frame having a head rigid therewith extending over said ram, an actuating lever pivotally mounted on the head of said frame, independent means releasably connecting said actuating lever to the respective pump plungers, and means releasably connecting said actuating lever to the tongue, whereby said actuating lever may be operated by the vertical swinging movement of said tongue or released from said tongue to permit free steering movement of said tongue, an exhaust conduit leading from said ram cylinder to said reservoir, a valve in said conduit, manually operable means for adjusting said valve to control the escape of fluid from said ram cylinder and thereby to regulate the rate of descent of said load supporting means, a relief conduit leading from said ram cylinder to said reservoir, and a spring-actuated relief valve for said conduit adapted to release fluid from said ram cylinder in response to pressure exceeding a predetermined amount.

10. An elevating truck comprising a frame having a rear axle and wheels thereupon, a head, steering mechanism rotatably mounted therein, a cylinder block located in proximity to said

head having a reservoir for a liquid, a central vertical ram cylinder, a plurality of pump cylinders having valved connections respectively with said reservoir and said ram cylinder, a ram reciprocably mounted in said ram cylinder, plungers reciprocably mounted in said pump cylinders, an actuating lever, means releasably connecting said actuating lever to the respective plungers, load supporting means having a head rigid therewith extending over said ram cylinder having anti-friction means to engage said ram whereby the upward movement of said ram will apply continuously a vertical lifting force directly to the front end of said load supporting means, a bell crank lever mounted on said frame having one arm pivotally connected to said load supporting means, a link connecting the other arm of said bell crank lever to a lifting member pivotally mounted upon said rear axle having at its end anti-friction means engaging the under face of said load supporting means and acting upon upward swinging movement of said lifting member to apply a lifting force vertically to said load supporting means.

11. An elevating truck comprising a frame having a rear axle and wheels thereupon, a head, steering mechanism rotatably mounted therein, a cylinder block located in proximity to said head having a reservoir for a liquid, a central vertical ram cylinder, a plurality of pumps having valved connections respectively with said reservoir and said ram cylinder, a ram reciprocably mounted in said ram cylinder, plungers reciprocably mounted in said pump cylinders, an actuating lever, means releasably connecting said actuating lever to the respective plungers, load supporting means having a head rigid therewith extending over said ram cylinder, a bell crank lever mounted on said frame having one arm pivotally connected to said load supporting means, a link connecting the other arm of said bell crank lever to a lifting member pivotally mounted upon said rear axle having at its end anti-friction means engaging the under face of said load supporting means, an abutment upon said frame intermediate of said bell crank lever and said axle, a stop adjustably mounted upon said link positioned to engage said abutment member to limit the upward movement of said load supporting means, and a conduit leading from said ram cylinder to said reservoir having therein a yieldable valve operable to relieve fluid pressure in said ram cylinder in excess of a predetermined amount upon continued action of said pumps after the arrest of the upward movement of said load supporting means by the engagement of said stop with said abutment.

12. An elevating truck comprising a main frame having a rear axle and wheels thereupon, a head and steering mechanism rotatably mounted therein, a hydraulic jack comprising a block located in proximity to said head having a reservoir for liquid, a vertical ram cylinder and a pump cylinder having valved communication with said ram cylinder, and means for actuating said pump, load supporting means having an integral head extending over said ram having an anti-friction roller to engage said ram, and means connecting said load supporting means to said frame comprising a bell crank lever pivotally mounted on said frame having one arm pivotally connected to said load supporting means and another arm connected by a link to a member pivotally mounted on said axle and having its free end provided with anti-friction means en-

gaging the under face of said load supporting means whereby upward movement of said ram will cause the load supporting means to be lifted vertically without substantial longitudinal movement relatively to the main frame.

- 5 13. An elevating truck comprising a frame having a rear axle and wheels thereupon, a head, steering mechanism rotatably mounted therein, a cylinder block mounted on said frame and located 10 in proximity to and rearwardly of said head having a reservoir for a liquid, and a central vertical ram cylinder, a pump having a valved connection respectively with the reservoir and said ram cylinder, a ram reciprocably mounted in said

ram cylinder, means for actuating said pump to raise said ram, load supporting means having a head rigid therewith extending over said ram provided with anti-friction means to engage said ram, whereby the upward movement of said ram will apply a vertical lifting force directly to the front end of said load supporting means, and means operable by the upward movement of the front end of said load supporting means having anti-friction means to engage the under face of the rear end of said load supporting means and to raise the same substantially vertically. 5 10
